(No Model.)

L. Z. JENKINS.

CHAMBER AND WATER BUCKET.

No. 357,390.

Patented Feb. 8, 1887.

Fig. 1.

UNITED STATES PATENT OFFICE.

LANCASTER Z. JENKINS, OF PHILADELPHIA, PENNSYLVANIA.

CHAMBER AND WATER BUCKET.

SPECIFICATION forming part of Letters Patent No. 357,390, dated February 8, 1887.

Application filed September 6, 1886. Serial No. 212,862. (No model.)

To all whom it may concern:

Be it known that I, LANCASTER Z. JENKINS, a citizen of the United States, residing in the city and county of Philadelphia, State of Pennsylvania, have invented a new and useful Improvement in Chamber and Water Buckets, which improvement is fully set forth in the following specification and accompanying drawings, in which—

10 Figure 1 represents a top or plan view of a chamber and water bucket embodying my invention. Fig. 2 represents an irregular vertical section thereof in line *x x*, Fig. 1.

Similar letters of reference indicate corresponding parts in the two figures.

My invention consists of a bucket adapted for emptying slops and supplying fresh water where required, the construction and operation being hereinafter fully set forth.

20 Referring to the drawings, A represents a bucket, which is divided into chambers B C by means of a vertical division-plate, D, secured within the bucket. The chamber B has a closed top, E, to which a screw-cap, F, is secured, whereby access is had to said chamber for supplying it with water. The chamber C has a hinged lid, G, whereby its interior is accessible. Within the chamber B, at the bottom thereof, are secured two cocks or valves, 25 H J, the valve H being in communication with said chamber B and the discharge-spout K thereof, and the valve J being in communication with both chambers B C. The valve stems or rods H' J' pass upwardly through the top E of the chamber B, and are provided with handles for operating purposes.

The operation is as follows: The valves are closed, and the chamber B is supplied with fresh or clean water, the bucket then being 30 carried to the required apartment. The chamber collections, dirty water in the bowl and basin, and stale water in the pitcher, or what is generally known as "slops," are poured into the chamber C, and the pitcher is replenished 35 with fresh water from the chamber B, this

latter being conveniently accomplished without overturning the bucket and spilling of the water by opening the valve H, so that the water escapes through the spout K, after which, when the pitcher is supplied, the valve H is 50 closed. The bucket is now carried to the water-closet or elsewhere, the lid or cover G opened, and the bucket overturned, so as to discharge the slops, after which the valve J is opened, whereby water from the chamber B 55 enters the chamber C and washes the latter, thus entirely removing the contents of the chamber and keeping the bucket clean and sweet.

Having thus described my invention, what I claim as new, and desire to secure by Letters Patent, is—

1. A bucket having a division-plate forming separate chambers and provided with a cock or valve forming a communication between the two chambers, whereby water in the one chamber may be directed into the other to wash the same, substantially as described.

2. A bucket having a division-plate forming separate chambers, a cock or valve in connection with a faucet which discharges the contents of said chamber, and another cock or valve forming a communication between the two chambers, the parts being combined and operating substantially as and for the purpose set forth.

3. A bucket with separate chambers therein, a closed top with an inlet for one chamber, a lid for the other chamber, valves within one of the chambers having operating-rods, and a discharge-spout connected with one of the valves, the other valve forming a communication between the two chambers, the several parts being combined and operating substantially as described.

LANCASTER Z. JENKINS.
